5 Claims. (Cl. 58—5)

1

This invention relates to mechanical calendars incorporated into or attached to clocks and provided with a disc indicating the months, one indicating the dates or days of the month and one indicating the days of the week.

Various embodiments of a clock having a mechanical calendar are already known. These known clocks are very complicated and difficult to make and to repair, have large dimensions and are expensive.

These disadvantages are avoided by the clock or the alarm having a mechanical calendar, or a separate unit for a suchlike clock, by the fact that a cam is secured upon a bushing for the hour-hand which bushing is rotatable in a disc. At each revolution this cam actuates a system of rods which suddenly moves the disc indicating the days one step. The disc indicating the days is provided with teeth or lugs which suddenly move the disc indicating the dates one step after each revolution or after every two revolutions by means of a pawl or a system of rods. This disc indicating the dates carries an abutment which also suddenly actuates the disc indicating the months after effecting a revolution or a certain portion of a revolution. The disc indicating the months is provided with abutments which are disposed at various distances from the centre of the disc in accordance with the number of days of the months. The clock or the separate unit according to the invention has very small dimensions, so that in a sturdy construction it can easily be positioned in a space having the dimension of the face of a normal clock or a normal alarm and having a depth of about a centimetre. The portion containing the elements of the mechanical calendar may be made independently of the clock, after which the clock may be secured thereto. Existing clocks may consequently be converted into a clock according to the invention in an easy way. Consequently the clock may be repaired wholly independently of the mechanical calendar. Furthermore it is thereby particularly suitable to be made in mass production. In addition, the advantage is obtained that the days, dates and months are changed over within a few seconds and that the exact date can be adjusted in a very simple way.

According to the invention the disc indicating the days may be divided into fourteen sectors of which two adjacent sectors indicate the same day, preferably in two different colours. The disc indicating the days includes fourteen pins co-operating with the system of levers ac-

2

tuated by the cam on the bushing for the hour-hand. By marking the sectors of each pair indicating each day in two different colours these colours may indicate whether it is before or after noon.

A preferred embodiment of the clock or of the separate unit for this clock according to the invention is characterized in that the system of levers for the actuation of the disc indicating the days comprises a bell cranklever provided with a return spring one leg of which lever co-operates with the cam on the bushing for the hour-hand and to the other leg of which a resilient pawl is pivoted in such a way that when the cam releases the lever from its extreme position the pawl rotates the disc indicating the days through a predetermined angle.

According to the invention the disc indicating the days may be constructed in such a way that it includes seven cams, pins or suchlike lugs which co-operate with the end of a pivoted lever provided with a return spring, which end is formed as a pawl. A resilient pawl is pivoted to this lever, which pawl co-operates with pawl teeth or other lugs of the disc indicating the dates and in operation rotates this disc further through a predetermined angle.

A preferred embodiment of the clock or the separate unit according to the invention is characterized in that the disc indicating the dates is provided with thirty-two sectors, one of which is blank and the other sectors of which are provided with the number 1—31. This disc has a same number of pawl teeth or lugs co-operating with the pawl actuated by the disc indicating the days. Together with this disc a stepped cam is pivoted, and a casing is secured thereon in which there is a spring which is stretched on rotation of the disc and which is prevented by a rotatable pawl from being released until this pawl, after the abutting of the stepped cam against one of the pins or lugs of the disc indicating the months, is released and locked, after which the disc indicating the days is returned into its initial position by the stretched spring, during which return the disc indicating the months is rotated one twelfth of a revolution by an abutment mounted upon the disc indicating the dates. It is clear that this disc indicating the dates may also comprise double the number of sectors, so that the same figure or number occurs twice on the disc in two adjacent sectors. In this case the construction of the clock or the separate unit is even simpler, since the

disc indicating the days can directly drive the disc indicating the dates.

According to the invention the clock may be made in such a way that the stepped cam comprises a pin passing through a slot of the disc indicating the dates, which pin serves to lift the pawl out of the pins or lugs co-operating with the pivoted pawl.

The locking member of the resilient pawl may consist according to the invention of a resilient counter-pawl which is released by a pin disposed on a fixed support when it is rotated backwardly.

A preferred embodiment of the clock or the separate unit is characterized in that the disc indicating the dates is provided with a pin or lug which actuates a system of levers provided with a pawl in such a way when rotating back the disc, that the disc indicating the months is rotated one twelfth part of a revolution.

According to the invention the separate unit may have a bushing in which the bushing for the hour-hand of any arbitrary clock may be fixed, and the hour-hand may be secured upon this bushing, whereas through this bushing and/or the spindle on which the minute-hand and/or the second-hand is or are secured passes or pass.

The invention will be explained more fully below with reference to the drawing in which by way of a non-limiting example an embodiment of a clock according to the invention is shown.

Figure 1 shows a front view of the clock.

Figure 2 shows on an enlarged scale a front view of the calendar mechanism with the hands and face of the clock removed.

Figure 3 also shows on an enlarged scale a cross section through the clock taken on line 3—3 of Fig. 2.

Figure 4 is a detail looking toward the rear surface of the disk on which the days of the week are provided.

Figure 5 is a view looking toward the rear surface of the intermediate disk on which the days of the month are provided, with part shown in section.

Figure 6 is a view looking toward the rear of the disk on which the names of the months are provided.

Figure 7 is a detail looking toward the front of the clock illustrating the cam for actuating the disk containing the names of the months with parts broken away.

Figure 8 is a detail showing the latch that holds the disc which indicates the days of the month, in the releasing position.

Figure 9 is a section taken on line 9—9 of Figure 7 showing the latch or pawl.

Figure 10 is a detail showing the upper end of the lever engaging the cam on the hour hand shaft of the clock.

Figure 11 is a detail illustrating a portion of the disk on which the days of the month are shown showing a blank space between the first and last numbers.

In the drawing which shows a unit suitable for attachment to a clock mechanism, three rotatable discs A, B and C are supported on a plate 26; disc A indicates the days of the week, B the dates or days of the months and C the names of the months. The front of the disc A is divided into fourteen sectors on which the days of the week each appear twice in adjacent sectors. The disc B indicating the dates has, in the embodiment shown, thirty-two sectors on which the numbers 1-31 are mentioned, sector one being left blank. The disc C indicating the months has

twelve sectors on which the months are shown in sequence.

The whole calendar mechanism is located behind a face 31 which is provided with three openings, opening 32 for the day, opening 33 the date and opening 34 the month respectively as shown in Figure 1.

A snail cam 2 is fixedly secured upon a bushing 1 which carries the hour hand of the clock. This cam 2 engages the end of a bell crank lever 3 pivotally mounted on a pin 35 whereby the arm 4 of the lever 3 is rocked together with a pivoted pawl 5 held by a spring 36. The lever 3 is spring loaded by spring 25 which maintains the bell crank against the cam 2. The cam 2 is disposed in such a way that each time the hour hand points to twelve the lever 3 drops off of the step in the cam and the spring 25 actuates the lever 3. Thereby the pawl 5 engages one of the pins 6 disposed at the back of the disc A whereby this disc is rotated one step. Thus at twelve o'clock midnight the disc A is rotated a step, whereby the name of the following day becomes visible through the opening 32 in the face of the clock.

This name is printed in black, for example, which indicates that it is before noon; at 12 o'clock midday the disc A is moved a further step to display the next sector on which the day is printed in red to indicate that it is afternoon.

The disc A carries seven cams 7. One of these cams 7 actuates at each second step of the disc A a pawl 9 resiliently held by a spring 31, and carried at the lower end of an arm 8, pivotally mounted on a pin 38, and provided with a return spring 39. This pawl 9 carries a pin 40 that engages pawl teeth 10, of which thirty-two are disposed circumferentially on the disc B. Hereby the disc B is rotated through a thirty-second part of a full revolution, to expose a new date at each movement through the window 33 in the face.

When the disc B is rotated, a cylinder 11 which is secured fixedly to the disc is also rotated, so that a spring 12 located therein is wound up (Figure 5) one end being secured to a stationary part of the device at the point 41, and the other to the cylinder 11 at the point 42. To the disc B a pawl 13 is pivoted on a pin 43, which cooperates with pins 14 fixedly secured to the plate 26 and prevents the spring 12 from releasing. When the disc B has rotated through twenty-eight (twenty-nine), thirty or thirty-one steps, a stepwise constructed cam 15 which is secured to the ring 15' and rotates with the disc B knocks against one of twelve pins 16 on the disc C indicating the months. The twelve pins 16 correspond with the number of months and are secured to this disc C and according to the number of days of the month, i. e. 28, (29), 30 or 31, are at various distances from the axis of rotation of the disc C. When the cam 15 comes into contact with one of the pins 16, the disc B continues to rotate, nevertheless, as long as the pawl 9 advances a tooth 10. The cam 15 is pivotally mounted by a pin 70 through the ring 15' and the cam carries a pin 17 which extends through a slot in the disc B, and presses against an extension of the pawl 13, until it is lifted out of the teeth 14 and is locked by a resilient counter-pawl 18, as shown in Figure 8. The pawls 13 and 18 are resiliently held by a spring 45 that is mounted on the disc B by a pin 46.

The ring 15' is resiliently held by a spring 11 so that the pin 17 is retained in the leading end of the slot 72 through the disk B.

As soon as the subsequent tooth 10 is released

by the pawl 9, the wound spring 12 rotates the disc B back through the whole angle through which it was rotated forward, until the counter-pawl 18 abuts against a pin 24 disposed on the plate 26, whereby the counter-pawl 18 releases the pawl 13 again and this comes into contact again with one of the pins 14. At the same time a pin 19 secured on the disc B has moved the arm 20 of a bell crank lever 21 which is pivotally mounted on the plate 26 by a pin 47, against the action of a return spring 48. Thereby the lever 21 takes along a pawl 22 pivoted thereto by a pin 49 and resiliently held by a spring 50, which rotates disc C by means of one of the twelve teeth 23 disposed circumferentially on the disc C by a pin 49', through a twelfth portion of a revolution, so that a new month appears in the window 34 of the face.

According as the cam 15 and the pin 16 corresponding with the month of February are disposed the clock will change over the mechanism after 28 or 29 days. In the former case the calendar need only be adjusted once in four years, and in the latter case three times in four years.

For the adjustment of the disc A indicating the days, the disc B indicating the dates and the disc C indicating the months the knobs 27, 51 and 52 are provided which actuate switching mechanisms 28, 29, 30 influenced by return springs 53 for the device 28, and 54 for the device 29, and these mechanisms co-operating with the pins 6 and the teeth 10 and 23. By this means each disc may be set or adjusted independently. The bar 28 may be slid upward by the knob 27 so that a tooth 56 thereon will engage one of the pins 6 on the back of the disc A, the arm 29 may be actuated by the knob 51 so that a pawl 57 thereon will engage the teeth 10, and the knob 52 may be moved downward in the slot 58 to engage the teeth 23 with the spring 30.

The clock calendar may be set at the beginning of the year with the numeral "1" in the window 33, the correct day of the week in the window 32, and the word "January" in the window 34, and after the disc B has been actuated thirty-one steps the step 60 of the cam 15 will engage one of the pins 16 of the disc C which will be held stationary by the pawl 22, wherein the cam 15 will turn about its pivot and actuate the pawl 13 which will release the disc B so that the spring 12 may return the disc to the starting position. For a thirty day month the step 61 of the cam 15 engages one of the pins 16, and for a twenty-eight or twenty-nine day month the end 62 of the cam engages the pin. With the pins arranged in the proper positions the disc B will be tripped so that it will be returned after the correct number of days for each month, and as it returns the counter-pawl 18 strikes the projection 24 and releases the pawl 13. Also in the return movement, a pin 19 on the disc B engages the arm 20 and sets the disc C ahead to the next month.

The plate 26 may be mounted on the face of a clock as shown in Figures 1 and 3 and the disc B is provided with a hub 63 by which it is rotatably mounted on the tubular clock shaft. The disc A is rotatably mounted on the plate 26 through a bearing 64, and the disc C is mounted thereon through a bearing 65.

It will be understood that the invention is not limited to the above-described embodiment but that the details thereof may be varied in several ways without leaving the scope of the invention.

I claim:

1. A mechanical calendar for a clock having an hour hand mounted on a shaft, a mounting plate having a centrally disposed opening to receive the said hour hand shaft, a plurality of discs having teeth on the peripheries positioned on said plate with a large disc in the center and a small disc at each side, means rotatably mounting the discs on the mounting plate, a cam mounted on the hour hand shaft, means rotating one of the small discs by the cam each time the hour hand makes one complete revolution, means actuated by the teeth on the periphery of the small disc for engaging the teeth of the large disc to advance the large disc one step each time the small disc advances two steps, resilient means returning said large disc to a starting position after it has traveled through a predetermined number of steps, and means actuated by the return movement of the large disc for advancing the other small disc one step.

2. A mechanical calendar for a clock having minute and hour hands with the hour hand mounted on a bushing, a mounting plate adapted to be positioned on the face of the clock with the hour hand bushing extending through a centrally disposed opening therein, a plurality of discs rotatably mounted on said mounting plate with a large disc in the center and a small disc at each side, a cam mounted on the said hour hand bushing, a bell-crank pivotally mounted on the plate with one arm engaging the surface of the cam, a pawl carried by the bell-crank adapted to actuate one of the small discs one step each time the hour hand makes a complete revolution, means rotating the large disc by the small disc actuated by the bell-crank, a latch holding the large disc, means releasing the latch after the large disc has rotated a predetermined distance, means returning the large disc to the starting position when the latch is released, and means actuating the other small disc by the large disc in the return movement thereof.

3. A mechanical calendar for a clock having an hour hand mounted on a shaft, a mounting plate having a centrally disposed opening to receive the said hour hand shaft, a plurality of discs having teeth on the peripheries positioned on said plate including a large disc in the center and a small disc at each side of the large disc, means rotatably mounting the discs on the mounting plate, a cam mounted on the hour hand shaft, a bell-crank pivotally mounted on the plate having two arms with one arm in engagement with the surface of the cam, a pawl carried by the other arm of the bell-crank adapted to engage a projection on one of the small discs to actuate said small disc one step each time the hour hand makes a complete revolution, a lever pivotally mounted on the plate positioned to be engaged by the teeth of the small disc actuated by the bell-crank, a pawl carried by the lever positioned to engage the teeth on the periphery of the large disc to advance the large disc one step each time the small disc is actuated two steps, a latch holding the large disc in each advanced position, a cam pivotally mounted on the large disc and positioned to engage projections on the other small disc, said cam adapted to release the latch as it engages one of the projections on the small disc, resilient means returning the large disc to a starting position when the latch is released, and means actuated by a projection on the large disc in the return movement thereof for advancing the said other small

disc one step with each of said return movements.

4. In a mechanical calendar as described in claim 3, means manually adjusting each of said discs independently.

5. A mechanical calendar as described in claim 3, wherein the cam is provided with a plurality of steps and the projections on the small disc are positioned at different distances from the center to compensate for the different number of days in the months.
